UNITED STATES PATENT OFFICE.

JOHN S. RATHBONE, OF MYSTIC, CONNECTICUT.

FOLDING PIPE-RACK.

1,104,004.

Specification of Letters Patent. Patented July 21, 1914.

Application filed April 30, 1913. Serial No. 764,608.

To all whom it may concern:

Be it known that I, JOHN S. RATHBONE, a citizen of the United States, residing at Mystic, in the county of New London and State of Connecticut, have invented certain new and useful Improvements in Folding Pipe-Racks, of which the following is a specification.

My present invention relates to a folding pipe rack and includes a novel arrangement of supporting elements designed to receive a plurality of pipes, said supporting elements being so arranged as to normally hold the pipes in an inclined position in order to prevent nicotine which is in the stem from running into the mouth piece.

The prime object of the present invention is to provide a supporting structure of the above mentioned type wherein the pipes are held in a normally inclined position, bowl downward, thus allowing the contents of the stem to flow to the bowl instead of the mouth piece.

Another object of this device is to provide a supporting rack designed with the above mentioned purpose in view which embodies suitable co-acting pipe receiving structures for supporting the pipes independent of each other, and in such manner as to guard against dislodgment thereof due to jarring or other usual causes.

A further object of this device is to provide suitable bowl receiving prongs for accommodating bowls of different diameters which allow the bowl to be readily removed when desired, yet it will positively prevent lateral movement which would otherwise result in the dislodging of the pipe.

A still further object of the present device is to provide a rack of the foregoing type, which is constructed of such parts which may be readily folded together in order to provide a compact and durable contrivance which is well suitable for the use before mentioned.

With the above and other objects in view, my invention relates to such details of construction, combination and arrangement of parts as will be hereinafter more fully described and specifically pointed out in the appended claims.

In describing my invention in detail, reference will be had to the accompanying drawings, wherein like characters denote like or corresponding parts throughout the several views, and in which;

Figure 1, is a perspective view of my invention, illustrating the rack in an upright position, Fig. 2, is an end elevation of the device showing the same when folded, 60 Fig. 3, is a plan view of the device when in a folded position, Fig. 4, is an end elevation of the rack in an upright position showing a pipe disposed thereon in the usual manner, Fig. 5, is a fragmentary 65 view of certain details illustrating the method of holding the operating parts of the rack in a rigid position when desired.

Referring now more particularly to the drawings wherein is illustrated the preferred embodiment of my invention, I have provided a suitable pipe supporting structure consisting of a body portion, formed of vertical and transverse standards and cross pieces 10 and 11 respectively, which are connected together at adjacent points by any suitable means in order to provide a completely rigid frame work. The body portion may be constructed of any desired material such as is best suitable for such demands.

The body portion mentioned has fastened thereon and in longitudinal relation therewith, an inclined stop member 12 which is disposed adjacent the upper extremity thereof and serves the purpose that will presently appear. The stop member may be also constructed of the same material as the body portion in view of the fact that I am not limited to any specific material to be used. 90 Other standards 13 have hinged connection with the standards 10 adjacent their upper extremities as shown at 14, upward movement of the standards being allowed through the medium of the stop member 12 as illustrated and consequently allowing the same to normally assume the position illustrated in Figs. 1 and 4 respectively. A transverse supporting element 15 connects the farther extremities of the standard 13 as shown at 16, in order to provide a comparatively rigid structure upon which the pipes may be disposed. For purpose of receiving the bowls of the pipes, a plurality of spaced apart aligned prongs are provided which extend at a substantially right angle in relation to the member 15 as illustrated, the latter being of course, supported at an angle as recognized.

I have provided suitable means for co-action with the supporting element 15 and the lower of the cross pieces 11 by which the

body portion and pipe supporting portion of the device may be held in rigid relation with each other when desired. With this in view, I have provided a fastening member 18 near 5 one end of which is hingedly connected as shown at 19, to the supporting element 15, while an opening 20 is provided adjacent its other extremity for reception of a pin 21 carried in the cut out portion 22 of the cross 10 pieces 11. This construction enables the operator to quickly and surely attain rigidity of the respective supporting elements of the device consequently allowing the rack to be set up very quickly. Means are further provided for accommodating the stems of the 15 pipes which project upwardly in alinement with the standards 13. This means comprises a transverse supporting element 23 which is hingedly connected to the respective 20 standards 13 as shown at 24 and has a plurality of cut out portions 25 provided therein, each cut out portion being in correct alinement with its adjacent bowl supporting 25 prong 17. With this in view, it is apparent that pipes of different characters can be easily disposed upon the rack, such as illustrated in Fig. 4, in such manner that the contents of the stem will flow toward the bowl portion instead of the mouth piece as would 30 usually be the case. This is the particular advantage presented over the usual pipe supporting rack now in vogue.

As set forth before, the parts of the rack may be constructed of any desirable material 35 consistent with the price for which the same is sold.

The advantages resultant from the use of my invention will be readily comprehended by those conversant with the crude and unsatisfactory devices, heretofore provided in 40 this art.

Such changes as are permissible by the subjoined claims may be resorted to without departing from the use of my invention.

Having thus fully described my invention, 45 what I claim as new and desire to secure by Letters Patent is:

1. A foldable pipe rack including a relatively movable section, a plurality of spaced apart prongs carried by the lower end of one 50 of said sections for receiving the bowls of pipes, a cross element pivotally connected to said last mentioned section, said cross element being arranged in spaced parallel relation with the lower end of said last mentioned section and provided with a plurality of cut out portions for receiving the stems of pipes supported by the adjacent prongs, 55 substantially as described.

2. A foldable pipe rack comprising a supporting frame, standards pivotally secured to the upper outer sides of said frame, a transverse supporting element secured to the outer ends of said standards, a plurality of spaced apart alined prongs secured to said 60 supporting element, a transverse cross piece pivotally secured to said standard, said cross piece provided with a plurality of spaced apart cut out portions, said cross piece being arranged parallel to said supporting element, 65 an inclined element secured to the upper end of said frame, said inclined element forming a stop for said standard, and a bracing bar pivotally secured to said supporting element, 70 the free ends of said bar bearing against the 75 lower end of said frame.

In testimony whereof I affix my signature in presence of two witnesses.

JOHN S. RATHBONE.
